UNITED STATES PATENT OFFICE

JOSEPH C. LEO, OF OELWEIN, IOWA

STERILIZER

Application filed June 29, 1931. Serial No. 547,763.

The present invention relates generally to sterilizers and more particularly to new and useful improvements in devices of this character for use in barber shops or beauty parlors and has for one of its important objects to provide, in a manner as hereinafter set forth, a sterilizer embodying a novel construction, combination and arrangement of parts through the medium of which all of the tools or instruments ordinarily used by a barber or beauty shop operator may be immersed in a sterilizing solution and conveniently removed without the necessity of getting the solution on the hands or fingers.

Other objects of the invention are to provide a sterilizer of the character described which will be simple in construction, strong, durable, efficient and reliable in use, attractive in appearance, compact, and which may be manufactured at low cost.

All of the foregoing and still further objects and advantages of the invention will become apparent from a study of the specification, taken in connection with the accompanying drawings wherein like characters of reference designate corresponding parts throughout the several views, and wherein:—

Figure 1 is a view in top plan of a sterilizer in accordance with the present invention.

Figure 2 is a view in top plan of the device with the hinged closures removed.

Figure 3 is a view in vertical longitudinal section through the sterilizer, taken substantially on the line 3—3 of Figure 2, looking in the direction indicated by the arrows and with the hinged closures in place.

Figure 4 is a fragmentary detail view in vertical longitudinal section taken substantially on the line 4—4 of Figure 2.

Figure 5 is a fragmentary detail view in horizontal section taken substantially on the line 5—5 of Figure 4, looking upwardly as indicated by the arrows.

Figure 6 is a fragmentary detail view in vertical longitudinal section taken substantially on the line 6—6 of Figure 2, looking in the direction indicated by the arrows.

Figure 7 is a fragmentary detail view in vertical cross section taken substantially on

the line 7—7 of Figure 2, looking in the direction indicated by the arrows.

Figure 8 is a fragmentary detail view taken substantially on the line 8—8 of Figure 2, looking in the direction indicated by 55 the arrows.

Figure 9 is a detail view in horizontal cross section taken substantially on the line 9—9 of Figure 3, looking downwardly as indicated by the arrows.

Figure 10 is a detail view in perspective of the swinging comb ejector.

Figure 11 is a fragmentary detail view in vertical cross section taken substantially on the line 11—11 of Figure 2, looking in the direction indicated by the arrows. 65

Figure 12 is a detail view in perspective of one of the springs which yieldingly urge the clipper ejecting plate toward its raised position.

Referring now to the drawings in detail, it will be seen that the sterilizer constituting the present invention comprises a substantially rectangular tank 1 of suitable metal for the reception of a sterilizing solution. 75 The tank 1 is closed at its top by a closure plate 2 which is secured in position by suitable means, such as the bolts 3.

Adjacent its rear edge, the plate 2 is provided with a series of longitudinally spaced 80 openings 4 of appropriate shape to receive razors of the straight type. Depending from the openings 4 into the solution in the tank 1 are the tubular casings 5 for the reception of the back portions of the razors which are 85 inserted through the openings 4. Each tubular casing 5 is provided with a vertical slot 6 extending from a point adjacent its lower end to its upper end and communicating with the openings 4. The slots 6 are for the reception of the razor blades and to permit the solution to enter the tubular casings 5. 90

Adjacent the openings 4, the plate 2 is further provided with a pair of openings 7 for 95 the reception of the blade portions of pairs of scissors to permit said blade portions to be immersed in the sterilizing solution in the tank 1. Of course, the handle portions of the scissors and of the razors will project above the 100

plate 2 in a manner to facilitate the removal thereof when desired.

Depending from the plate 2 is a well 8 for the reception of tweezers and finger nail files. The well 8 is provided with a bottom which is inclined at one end portion, as at 9, and said well bottom is provided with a plurality of perforations 10 to permit the sterilizing solution to enter the well for contact with the instruments therein. The well 8 is provided with a closure 9' which is hingedly mounted, as at 10 at one end to the plate 2. A suitable knob 11 is provided on the free end portion of the closure 9' for operating said closure.

The reference numeral 12 designates a cover for the openings 4 and 7 in the plate 2, said cover being hinged, as at 13, to the plate 2. If desirable or necessary, the lower side of the cover 12 may be suitably hollowed out for the reception of the outwardly projecting portions of the razors and scissors.

The reference numeral 14 designates an elongated, longitudinally extending well having a longitudinal partition 15 therein providing a pair of compartments for the reception of combs. The bottom of the well 14 is provided with perforations 16 to permit the sterilizing solution from the tank 1 to enter the well 14. Operatively mounted in the well 14 is a pair of comb ejectors 16' which are formed integrally with each other from a single length of wire which is bent in a manner to provide the spaced, parallel arms 17 disposed adjacent opposite sides of the partition 15 and terminating, at one end, in the outwardly turned comb engaging and supporting end portions 18. The other ends of the arms 17 merge with the eyes 19 which are for the reception of a suitable pivot pin 20 extending through the partition 15 for mounting the ejector for swinging movement thereon. The eyes 19, in turn, merge with the arcuate substantially U-shaped handle portion 21 which extends upwardly to provide means for manually operating the ejector. The upper portion of the partition 15 is recessed, as at 22, to facilitate operating the handle 21.

Secured to the lower side of the plate 2 and depending therefrom into the tank 1 is a container 23 for the reception of clippers. The container 23 is adapted to contain, if desired, a sterilizing solution which may be different from the sterilizing solution contained in the tank 1 and for this reason the bottom and vertical walls of the container 23 are imperforate. Access to the interior of the container 23 is had through an opening 24 provided in the plate 2. A swingable ejector plate 25 is hingedly mounted, as at 26, to the lower side of the plate 2 for operation in the container 23 and for disposition in the opening 24. The free end portion of the swinging ejector plate 25 is downwardly offset as at 27

for engagement beneath the plate 2 in a manner to limit the upward swinging movement of the ejector 25 under impulsion by the springs 28 which are mounted on the plate 2 and operatively engaged with the ejector 25. When in its raised position, the swinging ejector 25 is disposed substantially flush with the upper surface of the plate 2. The swinging ejector 25 is provided with a plurality of perforations 29. The reference numeral 30 designates a closure for the opening 24, said closure 30 being hingedly connected, as at 31, to the plate 2. The closure 30 is further provided with an operating knob 32.

The reference numeral 33 designates a closure for the comb receiving well 14, said closure 33 being hingedly connected, as at 34, to the plate 2. The reference numeral 35 designates an operating knob which is fixed on the closure 33. It may be well to here mention that the cover 12 is also provided with an operating knob 36.

The plate 2 is provided with a pair of openings for pouring the solutions into the tank 1 and the container 23, said openings being closed by the suitable plugs 37 and 38.

It will thus be seen that I have provided a sterilizer which is adapted to contain all of the tools or instruments customarily used by barbers or beauty shop operators. It will further be seen that the tools or instruments may be immersed in the solution to thoroughly sterilize the same and then conveniently removed without the necessity of bringing the fingers directly into contact with the solution.

It is believed that the many advantages of a sterilizer in accordance with this invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A sterilizer comprising a tank for the reception of a sterilizing solution, a closure plate mounted on the tank, and wells, for the reception of the articles to be sterilized, depending from the plate into the solution, one of said wells including a bottom having an inclined end portion extending upwardly to the closure plate, said wells having perforations therein for the passage of the solution thereinto for contact with said articles, the closure plate having openings therein communicating with the wells and providing access to said wells, and closures hingedly mounted on the plate and adapted for disposition over the openings in said plate.

2. A sterilizer comprising a tank for the reception of a sterilizing solution, a closure plate mounted on the tank, and wells for the

reception of the articles to be sterilized, mounted on the closure plate and depending therefrom into the solution, said wells having perforations therein for the passage of
 5 the solution thereinto for contact with said articles, a partition extending through one of the wells and providing a pair of comb receiving compartments therein, and a comb ejector mounted for swinging movement on
 10 the partition and engageable with one end portion of the combs for lifting said combs out of the compartments.

3. A sterilizer comprising a tank for the reception of a sterilizing solution, a closure plate mounted on the tank, and wells for the reception of the articles to be sterilized, mounted on the closure plate and depending therefrom into the solution, said wells having perforations therein for the passage of
 15 the solution thereinto for contact with said articles, a partition extending through one of the wells and providing a pair of comb receiving compartments therein, and a comb ejector mounted for swinging movement on
 20 the partition and engageable with one end portion of the combs for lifting said combs out of the compartments, said ejector comprising a length of wire bent upon itself in a manner to provide an actuating handle,
 25 said handle straddling the partition, eyes merging with the handle for engagement with the pivot pin for swingingly mounting the ejector in position, arms extending from the eyes adjacent opposite sides of the partition, said arms terminating in outturned free end portions for operative engagement with the combs in the compartments.

4. A sterilizer comprising a tank for the reception of a sterilizing solution, a closure plate mounted on the tank, a container secured to the plate and depending therefrom for the reception of a sterilizing solution, said plate having an opening therein communicating with the container, and a swinging ejector
 40 plate hingedly mounted on the first-named plate and operable in the container, said ejector plate being engageable with the first named plate for limiting the swinging movement thereof in one direction, and resilient
 45 means for yieldingly urging the ejector plate in said one direction.

5. A sterilizer comprising a tank for the reception of a sterilizing solution, a closure plate mounted on the tank, an imperforate container secured to the lower side of the closure plate and depending therefrom, said closure plate having an opening therein communicating with the container, said container being adapted for the reception of a sterilizing
 55 solution and being further adapted for the reception of an article to be sterilized, a swinging ejector plate operable in the container and hingedly connected to the closure plate for disposition in the opening, said
 60 ejector having an offset free end portion en-

gageable with the closure plate for limiting the swinging movement of the ejector in one direction, and springs mounted on the closure plate and engaged with the ejector for yieldingly urging said ejector in said one direction.

In testimony whereof I affix my signature.
 JOSEPH C. LEO.
